(57) **CLAIM**

The ornamental design for a center fascia for vehicle, as shown and described.

DESCRIPTION

FIG. 1 is a front, right perspective view of the center fascia for vehicle showing our new design in a first state of use; FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a front, right perspective view thereof in a second state of use in which the screen unit protrudes in the form of buttons;

FIG. 9 is a front view thereof;

FIG. 10 is a rear view thereof;

FIG. 11 is a left side view thereof;

FIG. 12 is a right side view thereof;

FIG. 13 is a top plan view thereof; and,

FIG. 14 is a bottom plan view thereof.

The broken lines depict portions of the center fascia for vehicle that form no part of the claimed design.

The present design is a dynamic design that can change from a basic screen state to a state in which buttons protrude from the screen unit.
